BOBBY PIN

Adolph Olevin, Brooklyn, N. Y.

Application August 13, 1951, Serial No. 16,248

Term of patent 14 years

(Cl. D86—10)

To all whom it may concern:

Be it known that I, Adolph Olevin, a citizen of the United States of America, residing in the Borough of Brooklyn, city of New York, county of Kings, and State of New York, have invented a new, original, and ornamental Design for a Bobby Pin, of which the following is a specification, reference being had to the accompanying drawing, forming part hereof.

Figure 1 is a view in perspective of a bobby pin showing my new design.

Figure 2 is a top plan view.

Figure 3 is an elevational view as might be seen from below Figure 2.

Figure 4 is an enlarged sectional view taken at the plane 4—4 on Figure 3.

I claim:

The ornamental design for a bobby pin, as shown.

ADOLPH OLEVIN.
